UNITED STATES PATENT OFFICE.

JAMES M. SMITH AND GEORGE J. FRITZ, OF BUTLER, NEW JERSEY; SAID FRITZ ASSIGNOR TO SAID SMITH.

BANJO.

SPECIFICATION forming part of Letters Patent No. 451,782, dated May 5, 1891.

Application filed December 9, 1890. Serial No. 374,064. (No model.)

To all whom it may concern:

Be it known that we, JAMES M. SMITH and GEORGE J. FRITZ, of Butler, in the county of Morris and State of New Jersey, have invented a new and useful Improvement in Banjos, of which the following is a full, clear, and exact description.

Our invention relates to an improvement in banjos, and has for its object to promote an increase of resonance in the instruments, giving them a full, heavy, clear, distinct, and bell-like tone.

A further object of the invention is to provide a means whereby a resonant ring will have a firm and secure bearing upon the rim and the strain exercised by the head upon the rim be equally divided all over the same.

The invention consists in a split or sectional resonant ring and in the novel construction and combination of the several parts, as will be hereinafter fully set forth, and pointed out in the claims.

Reference is to be had to the accompanying drawings, forming a part of this specification, in which similar figures and letters of reference indicate corresponding parts in all the views.

Figure 1 is a plan view of a banjo having the improvement applied and the head partially in section. Fig. 2 is an enlarged vertical section through the head, the rim, the ring, and their connections; and Fig. 3 is a similar section taken only, however, through the ring, the rim, and the parts connecting the two.

The resonant ring A is preferably made of metal, and is constructed in two horizontal sections 10 and 11, being substantially a split ring. The top and bottom surfaces are preferably cylindrical and the opposed inner faces are flat. The lower member of the ring is provided with a series of apertures extending through it at or near the center, and the upper member has threaded openings produced in its under face corresponding in number and location to the apertures in the lower member.

In connection with the ring a series of studs B is employed, the lower sections 12 whereof are preferably round, the upper section 13

being of less transverse area, and also round in cross-section. The difference in diameter of the said sections forms shoulders 14, and the upper ends of the reduced sections are threaded.

A number of recesses 15 is made in the upper edge of the rim 16, corresponding in cross-sectional contour to that of the lower section of the studs. The recesses are, however, of less depth than the length of the said stud-sections, and are provided with casings or ferrules 17, of metal or other hard substance, the rim being usually made of wood. The upper reduced sections of the studs are passed through the apertures in the lower member 65 of the resonant ring and secured in the threaded openings of the upper member. The two ring members are held some distance apart by washers 18, introduced between them and carried by the studs, and the studs are manipulated until the lower member of the ring rests upon their shoulders 14. The lower sections of the studs are introduced into the rim-recesses, and by reason of the difference between the depth of the recesses and the length 75 of the said stud-sections the shoulders 14 of the studs are above the top of the rim, and a space of, for instance, a quarter of an inch is thereby made to intervene between the rim and the ring. The head or covering-membrane is laid upon the ring, carried down beyond the sides thereof, and tightened in any well-known manner and with any approved form of device, the ordinary clamps being illustrated for that purpose in the drawings. 85

The members of the ring may be spaced and bolted or riveted together and the ring be attached to the rim otherwise than is illustrated; but the studs are preferred, as they insure an equal pressure upon the rim all 90 around its upper edge when the head is tightened, and the manner of connecting the rim with the ring effectually prevents any undue wear and tear upon the latter.

It will be understood that the studs may be 95 square in cross-section, or of other polygonal shape, if desired.

Having thus described our invention, we claim as new and desire to secure by Letters Patent—

1. In a banjo or similar instrument, a resonant ring formed of independent sections, substantially as shown and described.
2. In a banjo or similar instrument, a resonant ring consisting of two horizontal members and interposed washers, substantially as specified.
3. In a banjo or similar instrument, a resonant ring consisting of two horizontal members, washers interposed between said members, and studs secured to the members and extending downward beneath the under member, as and for the purpose specified.
4. In a banjo or similar instrument, the combination, with a rim provided with sockets or recesses, of a sectional resonant ring, spacing-blocks interposed between the members of the ring, and studs connecting the ring members, the lower ends of which studs en-
ter the rim-recesses, substantially as and for the purpose specified.
5. In a banjo or similar instrument, the combination, with a rim provided with sockets or recesses and a casing or ferrule of a hard substance introduced into each recess, of a resonant ring, spacing-blocks interposed between the members of the ring, studs connecting the ring members, the said studs being provided with shoulders to support the lower member of the ring, and the lower ends of said studs being adapted to enter the casings or ferrules secured in the rim, as and for the purpose specified.
